WERNER J. BLANCHARD, OF HEMPSTEAD, NEW YORK, ASSIGNOR TO CURTISS AERO-
PLANE & MOTOR COMPANY, INC., A CORPORATION OF NEW YORK

AERONAUTICAL PROPELLER

Application filed July 14, 1930. Serial No. 467,732.

My invention relates to aeronautical propellers and more particularly to one piece forged metal aeronautical propellers having thin solid blades and integral therewith 5 a central boss or hub forming enlargement.

The object of the invention is to so form and construct a one piece forged metal aeronautical propeller as to secure unusual strength, minimum weight, uniformity of 10 metal distribution, and decreased manufacturing cost.

Strength.—Maximum strength is obtained by reason of the fact that the tensile forces at or near the hub portion of the 15 propeller, instead of acting at an angle to the longitudinal axis of the propeller blades, acts in substantially a straight line and in parallelism with said axis. That this may be accomplished, the opposed blades, at or 20 near said hub portion, instead of being formed in or twisted to out-of-alignment relation, lie in substantially the same plane and are of substantially uniform thickness and width even at their point of juncture 25 with said hub forming enlargement.

Weight.—The weight of the propeller is approximately twenty percent less than its contemporaries. Reduction is achieved by the economical distribution of metal at or 30 near the hub, as well as by the complete elimination of that bulk of metal at or near the hub heretofore considered essential.

Uniformity of metal distribution.—Through a more uniform and hence better 35 distribution of the metal, a smoother running propeller is made possible and the forging operation very materially simplified.

Decreased manufacturing cost.—Production or manufacturing cost is lessened (a) 40 by the elimination of metal bulk, (b) by a simplification of the forging operation and (c) by the elimination of the heretofore required and separately obtained twisting of 45 the propeller blades. In the present invention, the propeller, instead of being forged in the rough and thereafter twisted, is forged with the blades twisted or rather pitched to the required angle. Only the 50 finishing operation, i. e., filing and polish-

ing, is left undone by the forging operation.

By the substantial decrease in production cost made possible in the manner indicated, plus the elimination of metal bulk, it is now possible to manufacture and sell, at a reasonable profit, solid forged metal propellers, in competition with wooden propellers of similar size or dimension. Since it is an established fact that metal propellers having thin and solid blades are more efficient 60 than the corresponding types of wooden propellers, obviously a step in the right direction in the advancement of the art of propeller manufacturing has been accomplished.

In the drawing, wherein like reference characters denote like or corresponding parts,

Fig. 1 is a face view of the propeller, and
Fig. 2 is an edge view or side elevation.

The propeller, as intimated, is of metal, preferably of an alloy of aluminum, such as duralumin, and is forged in one piece, and except for the filing and polishing, is completed in a single operation. As the two-blade propeller is by far the most common, this particular type of propeller has been selected for illustration.

The propeller comprises opposed blades 10—10 and a central integral hub forming 80 enlargement 11. The enlargement 11 is formed by the provision of opposed bosses 12—12 which extend out from the opposite faces of the blades 10—10 at the line of juncture of the blades, each boss or enlargement extending axially of the propeller and being of substantially uniform outside diameter and preferably substantially circular from end to end. In the interest of the 85 elimination of metal bulk each boss or enlargement has an over-all diameter substantially less than the over-all width of the blades at their point of juncture. The enlargements 12—12, together with the mid portions of the blades 10—10, form a hub of substantial length for accommodation on a suitable propeller shaft. The hub thus formed is preferably at least twice as long 90 as the longitudinal depth or thickness of the blades, to give an adequate mounting sur-

face to assume torsional and rocking stresses to which the propeller is subject.

The blades 10—10, for some little distance at opposite sides of the axis of rotation of 5 the propeller, are directly opposed, each making (see Fig. 2) a straight line continuation of the other. In other words, in the vicinity of the hub forming enlargement 11, the propeller blades are untwisted and of 10 almost uniform thickness and width. Thus constructed, the weight is reduced and at the same time the strength increased. By making one blade a straight line continuation of the other in the vicinity of the hub, 15 the forces acting thru the hub (where the propeller is most heavily stressed) act in direct opposition and in a manner such that better balance, a better distribution of metal bulk and substantially a twenty percent saving in weight is achieved. While it is apparent that in an aeronautical propeller the metal cannot be distributed in true uniformity, it is nevertheless felt that in the present embodiment, such a condition has 20 been more nearly approached than in any propeller heretofore designed or constructed. Moreover, by reason of the uniform distribution of metal, the forging operation is made easier and a great deal more dependable, 25 thus lessening the number of rejections heretofore encountered in the manufacture of one piece forged metal propellers.

While I have described my invention in detail in its present preferred embodiment, 30 it will be obvious to those skilled in the art after understanding my invention, that various changes and modifications may be made therein without departing from the spirit or scope thereof. I aim in the appended 35 claims to cover all such modifications and changes.

What I claim is:

1. A one piece forged metal aeronautical propeller comprising thin solid blades and integral therewith and on opposite faces thereof opposed hub forming enlargements, said enlargements, in each instance, being of circular section and of substantially uniform diameter, the diameter, in each case, 40 being substantially less than the width of the propeller at the line of juncture of the propeller blades, and the length, in each case, being substantially greater than the blade depth.
- 55 2. A one piece forged metal aeronautical propeller comprising thin solid opposed blades of substantially uniform thickness and width at the hub, the opposed blades, for at least the diameter of the hub, affording each a straight line continuation of the other, and integral with said straight line portion of the blades, and on opposite faces thereof, substantially cylindrical hub forming enlargements, said enlargements, in each 60 instance, extending axially of the propeller

and having a substantially uniform overall diameter not greater than the width of the propeller blades at the line of juncture therebetween.

3. A one piece metal aeronautical propeller comprising a pair of integral oppositely extending angularly pitched blades, and a centrally disposed hub forming enlargement integral with said blades, the portions of the blades adjacent the hub being untwisted and each being a straight line continuation of the other.

4. A one piece metal aeronautical propeller comprising a plurality of integral radially extending angularly pitched blades, and a centrally disposed hub forming enlargement integral with said blades, the portions of the blades adjacent the hub being untwisted and lying in a common plane normal to the axis of rotation of the propeller.

5. A one piece metal aeronautical propeller comprising a plurality of integral radially extending angularly pitched blades, and a centrally disposed hub forming enlargement integral with said blades, the portions of the blades adjacent the hub being untwisted and lying in a common plane normal to the axis of rotation of the propeller, said inner blade portions being joined one to another by continuations thereof enclosing said hub portion.

In testimony whereof I hereunto affix my signature.

WERNER J. BLANCHARD.
